UNITED STATES PATENT OFFICE.

HENRY HESS, OF PHILADELPHIA, PENNSYLVANIA.

PENCIL.

1,327,236.

Specification of Letters Patent.

Patented Jan. 6, 1920.

Application filed November 27, 1915. Serial No. 63,758.

To all whom it may concern:

Be it known that I, HENRY HESS, a citizen of the United States, residing at Philadelphia, in the county of Philadelphia and State 5 of Pennsylvania, have invented certain new and useful Improvements in Pencils, of which the following is a specification, reference being had therein to the accompanying drawing.

10 This invention relates to pencils, and has for its object the production of a pencil in which a comparatively slender marking lead or crayon may be employed without liability of breakage, and in which fresh portions of 15 the end of the lead may be exposed as the same becomes worn in use without the necessity of cutting away the inclosing holding body.

With this end in view, my invention consists in applying a reinforcing covering to 20 the slender marking lead so as to produce a core, and in inclosing this core in a suitable covering to produce a holding body, the said two coverings being of such form that they 25 may be removed in successive sections to expose the point of the lead. By this means, and on account of the slender or attenuated character of the marking lead, no sharpening or reduction in cross section of the same 30 will be necessary to produce a point fine enough for use, while at the same time the slender lead will be given such reinforcement as will enable the main covering or holding body to be applied without danger 35 of breakage of the lead.

In the accompanying drawings:

Figure 1 is a longitudinal section through a pencil constructed in accordance with my invention.

40 Fig. 2 is a view showing how the reinforcing covering is applied to the slender lead to produce a core.

Fig. 3 is a longitudinal section through the lead and reinforcing covering after the 45 application of the latter.

Fig. 4 is a view showing how the core produced by the application of the reinforcing covering is inclosed in the holding body to produce the completed pencil.

50 Referring to the drawings:

My improved pencil consists of a marking lead or crayon 1, which is of slender or attenuated dimensions so that it will not be necessary to cut away the material to produce a sufficiently fine point for use. In other words, by the employment of a narrow

or slender lead a marking point will be presented at all times of sufficient fineness for use. 2 represents a reinforcing covering which is applied to the lead for the purpose 60 of reinforcing the same and preventing its breakage, which would otherwise be apt to occur. The lead and covering thus applied forms in effect a core which is inclosed in a holding body 3 applied to the exterior of 65 the core. The reinforcing covering and inclosing body are of such construction and so applied that they may be removed in successive sections from the front end of the pencil to expose a fresh portion of the marking lead as the point wears away in use.

The reinforcing covering in the present instance is in the form of a flexible sheet 1^a preferably of paper, containing a series of parallel weakened lines 1^b and the sheet is 70 wound on the lead with the weakened lines in diagonal relation thereto, and when completely wound thereon it will present at its end a conical terminal portion 1^c made up of the ends of the overlapping spiral coils. 75 The length of the sheet is such that a core will be produced considerably less in diameter than the completed pencil, say $\frac{1}{8}$ of an inch in a pencil $\frac{5}{16}$ of an inch in diameter.

The inclosing body 3 consists of a sheet 80 3^a preferably of paper and containing parallel weakened lines 3^b, which strip is wound on the core in the same manner that the reinforcing strip is applied to the lead, but preferably with the weakened lines at a less angle 85 relatively to the axis of the lead. As a result the conical portion 3^c of the body, produced by the overlapping ends of the successive coils will extend at a less slope 90 or angle than the conical terminal portion 95 1^c of the reinforcing covering, the latter being therefore blunter and more abrupt, so that it will more strongly support the marking lead at its extreme effective point.

In the use of the pencil thus produced, 100 when the point of the marking lead becomes worn down, a section of the outer covering may be removed by tearing the same along the foremost weakened line 3^b. This will expose a limited portion of the inclosed surface of the reinforcing covering, and this in turn may be removed by tearing along the foremost weakened line 1^b so as to expose a suitable surface of the marking lead within.

110 While in the accompanying drawing and foregoing description I have disclosed my

invention in the specific form which I prefer to adopt, it will be understood that the invention is not limited to the particular details disclosed but that various changes, such as will suggest themselves to those skilled in the art, may be made without departing from the limits of my invention. For instance the reinforcing covering and inclosing body may be constructed of other and different forms, provided that the slender marking lead will be given proper support, and provided that the coverings may be removed in successive sections to expose fresh portions of the lead as the same becomes worn in use.

Having thus described my invention, what I claim is:

1. In a pencil, the combination of an attenuated marking lead or crayon, a flexible sheet wound thereon to produce a relatively thin preliminary covering for the lead to reinforce the same against breakage in subsequent handling, said sheet being provided with weakening lines to permit it to be removed from the lead in sections, and a second flexible sheet wound around the reinforcing covering and forming a stiff substantial holding body of relatively greater thickness than the reinforcing covering, said second sheet being also provided with weak-

ening lines to permit the same to be removed in sections.

2. In a pencil, the combination of a marking lead or crayon, a covering for the lead consisting of a paper sheet wound spirally thereon and producing a core, an inclosing holding body for the core consisting of a sheet wound spirally on the core at a different angle from that of the first sheet, the said sheets being adapted to be unwound and removed in successive sections to expose the point of the marking lead; whereby the inner covering will present a blunter terminal portion than that of the inclosing body and will more strongly support the point of the marking lead.

3. In a pencil, the combination of a marking lead or crayon, a covering applied thereto to reinforce the same and produce a core, and a second covering applied to the core to form a holding body, the ends of said two coverings sloping backwardly from the end of the lead, the reinforcing covering at a greater slope than the surrounding covering, and said two coverings being adapted to be removed in sections to expose the point of the marking lead.

In testimony whereof I have affixed my signature.

HENRY HESS.
